UNITED STATES PATENT OFFICE.

ARTHUR A. HAMERSCHLAG, OF PITTSBURGH, PENNSYLVANIA.

METHOD OF PRODUCING AN EXPLOSIVE MIXTURE.

1,093,406.

Specification of Letters Patent. Patented Apr. 14, 1914.

Application filed April 17, 1913. Serial No. 761,706.

To all whom it may concern:

Be it known that I, ARTHUR A. HAMERSCHLAG, a citizen of the United States, and resident of Pittsburgh, in the county of Allegheny and State of Pennsylvania, have invented certain new and useful Improvements in Methods of Producing an Explosive Mixture, of which the following is a specification.

10 This invention relates to the production of an explosive mixture for internal combustion engines from liquid hydrocarbons which, at atmospheric temperatures, are so deficient in vapor pressures as not to mix in 15 requisite amount with the necessary air component of the charge. It is, therefore, necessary to maintain the liquid at an efficient vaporizing temperature, and the accomplishment of this and the maintenance of other 20 requisite or highly desirable conditions are the prime objects of the present invention.

The hydrocarbon is preferably in the form 25 of a film when subjected to the vaporizing heat and to the air with which the vapor mixes in forming the explosive charges, whereby the vaporizing and the mixing processes have the benefit of a relatively large surface area which insures vapor in adequate amount and a thorough mixing of 30 the fuel elements. A further characteristic is the utilization of the film-holding surface as a heating medium, and, preferably, with such surface automatically controlling the temperature thereof, the flow of heat increasing and decreasing with increased and decreased demand on the carburetor. The 35 uniform conditions thus automatically maintained insure uniformity in the explosive mixture regardless of variations, within reasonable limits, of the amount consumed. The best results are obtained when the air 40 for the carbureting process is preheated, as it facilitates vaporization of the hydrocarbon and insures a more effective mixing of 45 the combustion elements than though the air were introduced cold. Also, less additional heat is required for maintaining the carbureting chamber and film-holding surfaces at vaporizing temperature. But the maximum 50 temperature of the preheated air should be lower than the automatically supplied heat so that the conditions controlled by the latter are not interfered with.

In the illustrated form of apparatus for 55 practising the invention, Figure 1 is a diagrammatic sectional elevation, and Fig. 2

and 3 are sectional plans taken on lines 2—2 and 3—3, respectively, of Fig. 1.

Referring to the drawings, 2 designates a vaporizing and mixing chamber with manifold 3 at its top provided with the requisite number of fuel outlets 4, one for each consumer of explosive mixture, as the cylinder of an internal combustion engine, not shown. The lower portion 5 of chamber 2 comprises 60 a holder for the liquid hydrocarbon which may enter through pipe 6, a valve 7 and float 8 automatically maintaining the level of 65 such fluid.

The film-maintaining surface is here 70 shown consisting of an upright open coil of wire mesh or netting 9, the lower ends of the convolutions being held in spaced relation at the bottom of chamber 2 by the notched holding bars 10, and the upper ends of the 75 convolutions are similarly held by one or more bars 11, all of said bars being formed of insulating material to prevent short-circuiting, as will presently appear.

The air inlet pipe 12 communicates with 80 the lower portion of chamber 2, and the screen convolutions are formed with series of air passages 14 located preferably in the plane of inlet 12 so that air is freely communicated to all of the convolution-separated 85 spaces of the screen. Inlet pipe 12 may be embraced by pipe coil 15 through which the jacket water of the engine cylinders may circulate, or through which the engine cylinders may exhaust, thereby heating 90 the air before it enters the vaporizing and mixing chamber.

A uniform temperature may be maintained within chamber 2 by electrical heating means. In the adaptation shown, coil 95 9 constitutes a resistance in an electric circuit 16, the circuit terminals being connected, respectively, to the inner and outer ends of the coil, as indicated at 17 and 18. The flow of current may be automatically controlled and a uniform temperature maintained in chamber 2 by means of a carbon pack 19 arranged in the circuit and operatively connected to the thermostat 20 projected into the chamber. The elements of 100 the automatic temperature controlling mechanism referred to are of familiar construction and need not be described in detail.

In operation, the liquid hydrocarbon is distributed over the screen convolutions by 110 capillary attraction, in this regard the action of the screen resembling a wick. A fluid

film of relatively large area is thus exposed to the vaporizing heat of the film supporting surfaces, and at the same time the inflowing air has free access to all of the film surfaces and thoroughly mixes with the vapor as the latter is generated. The foraminous film-holding surfaces are conducive to a thorough mixing of the air and vapor, affording opportunity for the air to freely circulate therethrough. The vaporizing and mixing actions are facilitated by the temperature of the inflowing air, and the pre-heating of such air reduces the amount of heat that otherwise would have to be supplied by the electric heating means. In order to maintain a uniform temperature within chamber 2 the inflowing air should not be heated to such a degree as to completely negative the electrical heating means, the latter embodying the automatic temperature control which is so adjusted as to define a desirable maximum temperature. The maintained temperature effectively vaporizes the hydrocarbon in such amount as to satisfy varying demands upon the carbureter, the flow of heat increasing with increased draft of mixed fuel, and decreasing with decreased outflow; as will be understood.

The vapor pressure of kerosene at atmospheric temperature is too low to be effective, and for this reason kerosene has been available as a motive fluid for automobile and other engines only after the engine has become heated sufficiently to produce the necessary vaporization. As kerosene could not be used for starting the engine it has been necessary to use gasoline until the engine has been thoroughly heated up. The apparatus for this double practice is cumbersome and costly, the gasoline and kerosene requiring separate tanks and carbureters. With the present invention these difficulties are overcome, the kerosene being available for starting regardless of the temperature of the engine, the kerosene exposed for vaporization being maintained in film form and its temperature from the beginning of the vaporizing process being such that the resultant vapor and air mixture contains vapor and air in proper proportions for combustion. While the requisite temperature need not be exactly predetermined it can be accurately approximated. As the heat supply necessary to maintain such temperature is automatically controlled by the temperature of the explosive charge before it leaves the carburetor, no difficulty is experienced in keeping it substantially uni-

form. And with such automatic control it is obvious that variations in the initial temperature of the kerosene, determined by the temperature of the atmosphere, are of no moment excepting that more heat is of course required, for instance, during cold winter weather than for the higher temperatures of summer.

The term "kerosene" is used in the claims to define any and all kinds and grades of liquid hydrocarbons that are so low in vapor pressure at atmospheric temperatures as not to combine with air in sufficient amount to form efficient explosive charges for internal combustion engines, but which by means of the invention herein disclosed may be utilized with as good effect as gasoline or other compounds that are sufficiently volatile and require no artificial vaporization.

The apparatus herein shown and described is merely illustrative of various forms of apparatus for practising the invention.

I claim:—

1. The method of producing an explosive mixture consisting in heating a film of kerosene to an efficient vaporizing temperature, utilizing such temperature for automatically maintaining the same, and subjecting the heated kerosene to a current of air.

2. The method of producing an explosive mixture consisting in producing a film of kerosene, heating the film-holding surface and automatically maintaining such temperature by thermostatic action, and subjecting the film to a current of air.

3. The method of producing an explosive mixture consisting in producing a film of kerosene, heating the film, controlling the temperature of the film automatically by means of its own temperature, preheating air to a lower temperature than that of the film, and subjecting the film to the action of the preheated air.

4. The method of producing an explosive mixture consisting in producing a film of kerosene, heating the film-holding surface to a film-vaporizing temperature, mixing air with the vapor from the film, and utilizing the temperature of the mixed air and vapor for controlling the temperature of the film-holding surface.

In testimony whereof I affix my signature in presence of two witnesses.

ARTHUR A. HAMERSCHLAG.
